[57] ABSTRACT

This invention refers to an air outflow device for ventilation plants for dwelling rooms, public rooms and other rooms comprising a casing with an inlet opening for pressurized air and within said casing a partition wall dividing the casing into a pressure chamber and a distribution chamber and having a slot shaped air passage opening. According to the invention, the air passage opening is formed as an air gap between an upwardly directed, tubular socket and a cap above said opening having a peripheral wall portion reaching downwards around the socket, the gap being adjustable by displacement of the cap towards and away from the partition wall for adjusting the width of the air passage opening between the socket and the cap to uniform values around its periphery so as to obtain a uniform and symmetric distribution of the air to the air distributing chamber and from this to the room.

AIR OUTFLOW DEVICE

In ventilation plants for dwelling rooms, public rooms and other rooms, the ventilation air flows from a duct opening in a wall or in the roof of the room through a grid or a vent in said duct opening. In order to avoid troublesome draft at the outflow of air into the room, the air pressure in the duct must be limited to certain maximum values. On the other hand it is desirable to maintain a higher pressure to obtain a stable ventilation. It is a purpose of the present invention to produce an air outflow device for ventilation plants in such a manner that an advantageous distribution of the air flowing out into the room can be obtained without troublesome draft in spite of a high air pressure maintained in the ventilation duct.

It is known to divide the housing of an air outflow device into a pressure chamber and an air distributing chamber by means of a partition wall comprising valve means for the control of the air passing from the pressure chamber to the air distributing chamber. In previously known structures the valve means have, however, been formed as valve flaps or valve slides which cause a less advantageous distribution of the air at the outlet.

This purpose is, according to the invention, mainly attained by the fact that the air passage opening in the partition wall is formed between an upwardly directed, tubular socket and a cap forming a lid over the socket opening and having a peripheral wall portion reaching downwards around the socket, the cap being adjustable towards and away from the partition wall for adjusting the width of the air passage between the socket and the cap to uniform values around its periphery so as to obtain a uniform and symmetric distribution of the air to the air distributing chamber and from this to the room. Since the slot-shaped air passage extends all around and can be adjusted, it is possible to adjust it so that the air pressure is reduced to a value appropriate for the distribution and outflow of the air through the grid.

Further characteristics of the invention and advantages derived therefrom will be found in the following description of an embodiment of the invention illustrated in the accompanying drawing which shows a perspective view of the device in section along a vertical median plane.

In the drawing, number 10 shows a casing with an air inlet opening 12 connected to an air duct (not shown), through which pressurized air is admitted. The casing 10 is by means of a partition wall 14 divided into a pressure chamber 16 above the partition and an air distributing chamber 18 below the same. An air passage slot 28 is formed between a surrounding wall 20 on a circular cap 22 and an upstanding socket 24 surrounding an opening 26 in the partition wall. The air flow resistance in this slot 28 can be adjusted by raising or lowering the cap 22 so that an inner wall 20 thereof is adjusted to a variable distance from the upper edge of the socket 24 extending into the cap.

A device for adjusting the air slot consists of a screw 32 with a circular guide head 34 for the inner ends of a number of levers 36, the outer ends of which are hingedly connected with the cap 22. For their guiding, the inner ends of the levers 36 can have slots which are en-

gaged by the edges of the guide head 34. The screw 32 engages a correspondingly threaded hole in a hub 38 fixedly supported by arms 40 fixedly mounted inside the socket 24 and supporting bearings 42 for the levers 36.

The air distributing chamber 18 is open downwards and its opening is covered by a grid 44 through which the air flows out into the room. The screw 32, which can have a slot 46 for a screwdriver in its head, can be made accessible by taking off the grid. The grid can have an upstanding frame 48 around its edges and an upstanding flange on this frame can have series of air outlet openings 50 which can be covered more or less by a wall portion 52 of the partition wall 14 by displacing the frame more or less into said wall portion.

Since the air is supposed to be admitted through the inlet opening 12 in the casing 10 at a relatively high pressure and a relatively high air flow velocity is obtained through the air slot 28, it is recommended to place a pad of sound insulating material 54 in the cap 22 and another such pad 56 in the casing 10.

A special advantage of the described device is that a heating of the air can be obtained e.g. by an electric resistor winding 58 around the downwards reaching wall 20 of the cap 22.

What we claim is:

1. An air-distributing device for ventilation plants for rooms, comprising a casing having an inlet for pressurized air, a partition dividing the casing into a pressure chamber and a distribution chamber, a wall closing the distribution chamber and having a plurality of outlets therethrough, said partition having an opening therethrough, a tubular socket surrounding said opening and outstanding from said partition, a cap in alignment with said opening and having a peripheral wall that encompasses said tubular socket to form an annular air passage between said peripheral wall and said tubular socket, and means to adjust the position of the cap toward and away from the tubular socket to control a quantity of air passing from said pressure chamber through said opening and air passage thereby to obtain a uniform and symmetric distribution of the air to the distribution chamber and from the distribution chamber through said outlets to the room.

2. An air outflow device as claimed in claim 1 in which the means for adjusting the air gap comprises of a screw with a guide head for the inner ends of a number of levers, the outer ends of which are hingedly connected with the peripheral wall of the cap.

3. An air outflow device as claimed in claim 2, characterized in that the screw is accessible for adjusting the air gap after removal of the first-mentioned said wall.

4. An air outflow device as claimed in claim 2, characterized in that the screw is screwed into a screw-threaded hole in a hub fixedly supported by arms fixedly mounted in the socket and themselves supporting bearings for the levers.

5. An air outflow device as claimed in claim 1, characterized in that said peripheral wall of the cap is surrounded by a heating winding for heating the air flowing past said peripheral wall.
